UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

FOLDING APPARATUS FOR PRINTING-PRESSES.

938,364.

Specification of Letters Patent. Patented Oct. 26, 1909.

Application filed September 23, 1908. Serial No. 454,332.

To all whom it may concern:

Be it known that I, HENRY F. BECHMAN, of Battle Creek, in the county of Calhoun and State of Michigan, have invented certain new and useful Improvements in Folding Apparatus for Printing-PresSES; and I hereby declare that the following is a full, clear, and exact description thereof, reference being had to the accompanying drawings, which form part of this specification.

This invention is an improvement in paper folding means and has particular reference to rotary folding mechanisms for use in connection with web-printing newspaper presses; and its object is to provide a rotary folder which will be capable of operating at very high speed with smoothness and certainty, and in which the action of the tucker-blades will be positively controlled at all times, and absolute uniformity in operation be obtained.

I will describe the invention in detail as embodied in the mechanism illustrated in the accompanying drawings; and summarize the parts and combination of parts for which protection is desired in the claims following said description.

The accompanying drawings illustrate a rotary web cutting and folding mechanism embodying the invention and particularly adapted for use in connection with rotary web-printing presses.

In said drawings—Figure 1 is an end elevation of the complete folding apparatus. Fig. 2 is a side elevation thereof, partly broken away. Figs. 3, 4 and 5 are enlarged detail views, partly in section and partly broken away, illustrating the operation of the tucker blades and their controlling devices. Fig. 6 is a detail sectional view of the folding rolls and tucker blade. Figs. 7 and 8 are detail sectional and face views of one of the rotary race-ways detached. Figs. 9 and 10 are detail end and side views of one of the tucker blades and its tumbler-levers.

In said drawings 1 designates a cutting and folding cylinder, of usual construction, and 2 the cutting or knife cylinder co-acting therewith and which cylinders are provided with intermeshing gears 1^a, 2^a, as usual, so as to have the same peripheral speed. Cylinder 1 is twice the diameter of cylinder 2 and is provided with two diametrically opposite cushions 1^b respectively adapted to co-act with the blade 2^b in cylinder 2 and

sever the web of paper, indicated at w, which is fed down to the cutting cylinders by rolls w, w', which are usually located at the apex of a "former", not shown. The web may be led to the rolls w, w', from any web printing or manipulating mechanism.

Within the cylinder 1 are two diametrically opposite shafts 3, which may be rotatably journaled in the cylinder as usual or in any suitable manner, and which carry opposite tucker blades 3^a; said shafts 3 project at each end beyond the ends of the cylinder 1 and are provided on their extremities with tumbling-levers 3^b, 3^c, which levers are provided on opposite ends with outwardly projecting pins 3^c, 3^e, which pins may be provided with rollers if desired. The pins 3^c, on tumblers 3^b, are adapted to engage with a guide-ring or race-way 4 which is secured to one of the side frames F by bolts 4^a, see Figs. 1 and 2,—while the pins 3^e, on the tumbling levers 3^c, are adapted to engage a guide ring or race-way 4^b secured to the opposite side frame F' by bolts 4^c, as shown in Fig. 2. These race-ways 4, 4^a control the position of the tucker blades 3^a and normally keep them retracted within the cylinder, as shown in the upper part of Figs. 1 and 2, but permit these blades to be operated at the proper time to tuck the sheets 5, 5^a, which are located at one side of the cylinder 1, and are shown at the lower side thereof.

The cutting and folding cylinders 1 is customarily provided with pins or devices 90 adapted to engage the lead end of the sheet of paper before it is severed by the blade 2^b and carry the same a proper distance beyond the folding rolls 5, 5^a, until the sheet is in position to be tucked therebetween. These 95 devices are well known and form no part of the present invention and I have not attempted to illustrate them within the cylinder as they would complicate the drawings. Furthermore while I have illustrated the 100 invention as applied to an ordinary form of folding apparatus and folding cylinder 1, the invention is not restricted to use in connection with such a cylinder, as any rotary support or carrier adapted to move the 105 tucker blade shafts laterally in an orbital path adjacent to the folding rolls may be employed in place of the cylinder 1. These folding rolls 5, 5^a are constructed substantially as usual, the roll 5^a in this instance 110

being journaled in brackets 5^b, attached to the side frames F, F', while the roll 5 is journaled in vertical arms 5^c, pivoted on bolts or studs 5^a attached to side frames F, 5 F'. Each of said arms 5^c has a laterally projecting portion 5^e which is pivotally connected to a rod 5^f that depends through an eye-stud 5^g, and a stout spring 5^h is interposed between the stud 5^g and a collar 5ⁱ on the rod; the tension of spring 5^h is regulable by a nut 5^j screwed on the lower end of rod 5^f below studs 5^a. By these means the roll 5 is held with a yielding pressure against roll 5^a. The rolls 5, 5^a, are provided with intermeshing gears 5^k, one of which gears meshes with a pinion 6^a on the inner end of a shaft 6, journaled in bearings in the side frames, beside the rolls and having on one end a pinion 6^b meshing with an intermediate 6^c which in turn meshes with gear 1^c on the shaft 1^s of cylinder 1. This arrangement of gearing of course could be changed to suit the particular design of the machine or folder to which the invention is applied.

25 The guide-rings or race-ways 4, 4^b, are cut away adjacent the rolls 5, 5^a, as indicated in the drawings, so that when the tucker blades reach the rolls 5, 5^a, and while they operate in connection with said rolls, they are under 30 the control of positively operating rotary devices arranged as follows.

Below the guide-ring 4 is a rotary race-way 7 which is formed on the surface of a disk 7^a, see Figs. 7 and 8, said race-way 35 being about 120 degrees in length and being concentric to the axis of said disk, which is provided with a stub-shaft 7^b journaled in the side frame F and has a gear 7^c on its outer end meshing with a pinion 7^d journaled on a stud attached to the side frame F and in turn meshing with a gear 7^e on the shaft 1^s of cylinder 1, the gears being so proportioned that race-way 7 makes two orbital rotations for each rotation of cylinder 40 1. The race-way is so located and the gearing so proportioned that the lowermost pin 3^e on the tumbling lever 3^b which is descending at the side of the cylinder 1, next to cylinder 2, will enter the advancing end of the 45 race-way 7 just as said pin reaches a position above the roll 5^a (see Fig. 3) and said race-way will take control of the said tumbling lever and cause said lever to operate the connected tucker-blade so as to tuck the 50 paper between the rolls 5, 5^a, (see Fig. 6) as hereinafter explained. The rotary race-way 7 co-acts successively with the tumbling levers 3^b on the shafts 3, but disengages said levers after the blade has been caused to 55 tuck the paper between the folding rolls 5, 5^a, at and after which time the blade passes into the control of another rotary race-way 8, constructed like race-way 7, located at the 60 opposite side of the machine, below the 65 guide-ring 4^b; said race-way 8 being formed

on a disk 8^a having a stub-shaft 8^b, journaled in the side-frame F', on the outer end of which stub-shaft is keyed a pinion 8^c meshing with an intermediate 8^d which in turn meshes with a gear 8^e on shaft 1^s of cylinder 1; the gearing being so proportioned that the race-way 8 is rotated twice for each revolution of the cylinder 1 and is rotated in the same direction as race-way 7. The race-way 8 is similar in construction to race-way 7 and it is unnecessary to illustrate it separately in detail in the drawings. The race-way 8 is arranged to engage the pins 3^e, on the tumbling levers 3^b, when either shaft to which said levers are attached 80 is at the lower side of cylinder 1 and directly over the rolls 5, 5^a, (see Figs. 4-6). And the rotary race-way 8 engages one of the pins 3^e of such lever at the moment that race-way 7 surrenders control of the related 85 lever 3^b at the other end of the shaft. The operation of these rotary race-ways will be more readily understood by reference to Figs. 3, 4, 5 and 6 of the drawings.

Fig. 3 shows the position of parts when 90 one set of tucking-blades 3^a is in position to commence a tucking operation. At this time one of the pins 3^e has left the lower end of ring 4 and has entered the upper end of the rotary race-way 7 which is turning toward the advancing tucker-shaft 3 in a direction contrary to the direction of travel of the tucker blade shaft. As the shaft 3 is moved laterally by the cylinder it follows that the pin 3^e is retarded and directed 95 downwardly by the rotary race-way 7, and as the shaft 3 advances to the position shown in Fig. 4 the blade 3^a is caused to tuck the papers between the rolls 5, 5^a, as indicated in Fig. 6. By this time however the rotary race-way 7 has advanced so that it is almost ready to leave the pin 3^e, on tumbling lever 3^b, but at this same moment the lowermost pin 3^e, on the tumbling-lever 3^b, on the opposite end of shaft 3 is just in position to enter 100 the forward end of the race-way 8, which is rotating in the same direction as race-way 7, as indicated in Figs. 4 and 6; and as shaft 3 travels on, pin 3^e is entered in race-way 8, and in connection with the movement of 105 shaft 3 the tumbling-lever 3^b completes the half revolution of the shaft 3 and brings the tucker-blades away from the folding rolls, and the pins 3^e, 3^e, are laid against the rings 4, 4^b.

As indicated in Fig. 5 the race-way 8 releases the pin 3^e just as it passes onto the receiving end of the ring 4^b. It will be seen that the operation of either set of tucking blades 3^a is accomplished by the successive 110 operation of race-ways 7 and 8; race-way 7 operating on one end of the rock-shaft to cause the blade to tuck the paper between the rolls, and then the blade is withdrawn 115 from the rolls and directed back into the 120

cylinder by the operation of the other rotary-race-way 8 and tumbling lever at the opposite end of the shaft. Also that the race-ways 7 and 8 operate successively and 5 not simultaneously, and at opposite ends of the cylinder, and on opposite ends of the tucker-blade shafts. And one race-way controls the tucking movement of the blade or projection of the blade out of the cylinder, 10 and the other race-way 8 controls the retraction of the tucker-blade or its withdrawal into the cylinder. It will also be observed, that the race-ways 7 and 8 move in a direction opposite to the line of movement of the 15 tumbling-lever pins (3°, 3°) with which they co-act at the time of engagement therewith, and that the change of control of a tucker blade shaft from race-way 7 to race-way 8 is effected at the time where there is a momentary dwell, or dead center, in the movement 20 of the lowermost pins (3°, 3°) on the tumbling-levers connected to the operating tucker-blade shaft. And the length of the race-ways 7 and 8 and their speed of movement is so proportioned that they do not interfere with each other in their action on the 25 pins or tumbling-levers.

By the aforesaid construction and arrangement of parts the tucker-blades are operated 30 with smoothness and without shock of impact against unyielding surfaces; and the folder will operate efficiently and quickly and with less noise than in the old construction wherein the tumbling-lever is operated 35 by pins engaging slots or notches in the rings; and the tucker-blades moreover will be projected and retracted more slowly, comparatively speaking, than in the old construction and therefore will operate more 40 certainly and uniformly.

While I have described the operation in connection with one set of the tucker blades 3°, it is obvious, that every other set of tucker-blades in the cylinder will be operated 45 in exactly the same manner when they reach the folding rolls; and any desired number of tucker-blades can be used in the cylinder.

It should be noted that when the tucker-blades are in projected position, as indicated 50 in Figs. 4 and 6, the lowermost pins 3° and 3° are at dead center, but the tucker-shaft and blade will be firmly held by the co-action of the race-ways 7 and 8 which still 55 control the respective pins 3° and 3°. Neither pin 3° nor 3° reverses its movement however in its race-way. The pins 3° pass entirely through race-way 7, and the pins 3° pass entirely through race-way 8, each pin 60 entering one end of its race-way and leaving at the other end thereof.

Having described my invention what I claim as new and desire to secure by Letters Patent thereon is:

65 1. In combination, folding rolls, a tucker

blade, and means for moving said blade laterally past the said rolls, with a pair of rotary devices one of which is adapted to cause the blade to tuck a sheet between the rolls and the other of which is adapted to retract 70 the said blade, the said devices moving in a direction contrary to the direction of lateral movement of the tucker blade at the times and points of their operation thereon.

2. In combination, a pair of folding rolls, 75 a tucker blade, and means for moving said blade laterally in an orbital path adjacent the said rolls, with a pair of rotary race ways one of which is adapted to cause the blade to tuck a sheet between the rolls and 80 the other of which is adapted to retract the tucker blade, the said race ways moving in a direction opposite to the direction of lateral movement of the tucker blade at the times and points of their operation thereon. 85

3. In combination, folding rolls, a tucker blade, and means for moving said blade laterally past the said rolls, with a rotary device adapted to project the tucker blade between the rolls, a second rotary device adapted to retract the tucker blade, and means for rotating both the said devices in the same direction, the said devices moving in a direction contrary to the direction of lateral movement of the tucker blade at the times 95 and points of their operation thereon. 95 98

4. In combination, a pair of folding rolls, a tucker blade, and means for moving said blade laterally in an orbital path adjacent the said rolls, with a pair of rotary race 100 ways one of which is adapted to project the tucker blade between the rolls and the other of which is adapted to retract the tucker blade, said race ways operating alternately on the blade, and means for rotating both race ways in one direction, the said race ways moving in a direction opposite to the direction of lateral movement of the tucker blade at the times and points of their operation thereon. 105 110

5. In a folding mechanism, the combination of cutting and folding cylinders, a tucking blade in the folding cylinder and moved laterally thereby, and a pair of rotary devices adapted to respectively cause the projection and the retraction of the tucker blade, the said devices moving in a direction contrary to the direction of lateral movement of the tucker blade at the times and points of their operation thereon. 115 120

6. In a folding mechanism, the combination of cutting and folding cylinders, a shaft carrying tucking blades, in the folding cylinder and moved laterally thereby, tumbling levers on the shaft, and a pair of rotary members adapted to alternately engage the tumbling levers to cause the projection and retraction of the tucker blades, said rotary members at the points of engagement with the tumbling levers traveling in a direction 125 130

contrary to the lateral movement of the tucker blades.

7. In a rotary folder, the combination of a folding cylinder, a shaft therein carrying tucker blades and provided with tumbling levers on its ends and moved laterally by the cylinder, folding devices beside the cylinder, and a pair of rotary members adapted to alternately engage the tumbling levers to 10 respectively cause the tucker blades to tuck a sheet between the rolls and to withdraw therefrom, said rotary members at the points of engagement with the tumbling levers traveling in a direction contrary to the lateral movement of the tucker blades.

8. In a folder, the combination of a folding cylinder, a shaft therein carrying a tucker blade and provided with tumbling levers on its ends and moved laterally by the cylinder, a pair of folding rolls beside the folding cylinder, and rotary race ways adapted to alternately engage the tumbling levers to cause the tucker blade to tuck a sheet between the rolls and to withdraw 25 therefrom, the said race ways moving in a direction opposite to the direction of lateral movement of the tucker blade at the times and points of their operation thereon.

9. In a folder, the combination of folding 30 and cutting cylinders, a shaft in the folding cylinder carrying tucker-blades and provided with tumbling levers on its ends and moved laterally by the cylinder, a pair of folding rolls beside the folding cylinder, and 35 rotary members adjacent the folding rolls and at opposite ends of the folding cylinder adapted to alternately engage the tumbling levers to cause the tucker blades to tuck a sheet between the rolls and to withdraw 40 therefrom, said rotary members at the points of engagement with the tumbling levers traveling in a direction contrary to the lateral movement of the tucker blades.

10. In a folder, the combination of folding 45 and cutting cylinders, a pair of folding rolls beside the folding cylinder, a shaft journaled in the folding cylinder and carrying tucking blades, and tumbling levers on the ends of the shaft said shaft being moved laterally by the cylinder; with a rotary member 50 at each end of the cylinder, one of said members being adapted to engage one tumbling lever to cause the blades to tuck a sheet between the rolls, and the other of 55 said members being adapted to engage the opposite lever to cause the retraction of the blade from the rolls, said rotary members at the points of engagement with the tumbling levers traveling in a direction contrary 60 to the lateral movement of the tucker blades.

11. In a folder, the combination of folding 65 and cutting cylinders, a pair of folding rolls beside the folding cylinder, a shaft journaled in the folding cylinder carrying tucking blades, and tumbling levers on the

ends of the shaft said shaft being moved laterally by the cylinders; with a pair of rotary race ways located at opposite ends of the cylinder, one of said race ways being adapted to engage one of the tumbling levers 70 to cause the blades to tuck a sheet between the rolls and the other of said race ways being adapted to engage the opposite lever and retract the blade from the rolls, the said race ways moving in a direction opposite to the 75 direction of lateral movement of the tucker blades at the times and points of their operation thereon.

12. In a folding mechanism, the combination of cutting and folding cylinders, tucking blades in the folding cylinder and moved laterally thereby, tumbling levers connected with said blades, a pair of rotary race ways adapted to alternately engage the tumbling levers to cause the projection and retraction 80 of the tucker blades; said rotary race ways being arranged at opposite ends of the cylinder and rotating in the same direction, the said race ways moving in a direction opposite to the direction of lateral movement of 85 the tucker blades at the times and points of their operation thereon.

13. In a folding mechanism, the combination of cutting and folding cylinders, a shaft in the folding cylinder carrying tucker 90 blades and moved laterally by the cylinder, tumbling levers connected to opposite ends of said shaft, a pair of rotary race ways located at opposite ends of the folding cylinder and rotating in the same direction, and 100 adapted to alternately engage the tumbling levers to cause the projection and retraction of the tucker blades, the said race ways moving in a direction opposite to the direction of lateral movement of the tucker blades at 105 the times and points of their operation thereon.

14. In a folding mechanism, the combination of cutting and folding cylinders, tucking blades in the folding cylinder and moved 110 laterally thereby, tumbling levers at opposite ends of the folding cylinder connected with said blades, and a pair of rotary race ways adapted to alternately engage the tumbling levers to cause the projection and 115 retraction of the tucker blades; said rotary race ways being arranged at opposite ends of the folding cylinder, the said race ways moving in a direction opposite to the direction of lateral movement of the tucker blades 120 at the times and points of their operation thereon.

15. In a folder, the combination of folding 125 and cutting cylinders, a pair of folding rolls; tucker blades in the folding cylinder and moved laterally thereby, tumbling levers connected with said blades, guide rings for said levers, and a pair of rotary race ways adapted to engage said levers and respectively cause the projection and retrac- 130

- tion of the tucking blades, the said race ways moving in a direction opposite to the direction of lateral movement of the tucker blades at the times and points of their operation 5 thereon.
16. In a folder, the combination of folding and cutting cylinders, a pair of folding rolls, shafts in the folding cylinders carrying tucker blades and moved laterally by the cylinder, tumbling levers on the opposite ends of each of said shafts, guide rings for said levers, and a pair of rotary race ways adapted to alternately engage the levers and respectively cause the projection and retraction of the tucking blades, the said race ways moving in a direction opposite to the direction of lateral movement of the tucker blades, at the times and points of their operation thereon. 10
17. In a rotary folder, the combination of folding and cutting cylinders, folding devices beside the folding cylinder, tucking blades in said cylinder and moved laterally thereby, tumbling levers connected with each of said blades at opposite ends of said cylinder, rotary members adjacent the folding rolls and at opposite ends of the cylinder adapted to alternately engage the said tumbling levers to respectively cause the projection and retraction of the tucking blades, said rotary members at the points of engagement with the tumbling levers traveling in a direction contrary to the lateral movement of the tucker blades. 15
18. In a rotary folder, the combination of folding and cutting cylinders, a pair of folding rolls before the folding cylinder, shafts journaled in said folding cylinder carrying tucking blades and moved laterally by the cylinder, tumbling levers on opposite ends of each of said shafts, and rotary race ways, adjacent the folding rolls and at opposite ends of the cylinder, adapted to alternately engage the said tumbling levers to respectively cause the projection and retraction of the tucking blades, the said race ways moving in a direction opposite to the direction of lateral movement of the tucker blades at the times and points of their operation 20 thereon.
19. In combination, cutting and folding cylinders, folding devices beside the folding cylinder, tucker blades in the folding cylinder and moved laterally thereby, tumbling levers attached to opposite ends of each of said blades, a rotary race way at each end of the folding cylinder, means for simul- 25
- taneously rotating the said race ways in the same direction, one of said race ways engaging one of the tumbling levers to cause the tucker blades to direct the sheet into the folding devices, and the other of said rotary race ways engaging the other tumbling lever to cause the retraction of the tucker blades, the said race ways moving in a direction opposite to the direction of lateral movement of the tucker blades at the times and points of their operation thereon. 30
20. In a rotary folder, the combination of cutting and folding cylinders, folding devices beside the folding cylinder, a shaft journaled in the folding cylinder carrying tucker blades and moved laterally by the cylinder, tumbling levers attached to the opposite ends of said shaft, a rotary race way adjacent each end of the folding cylinder; means for rotating the said race ways, said rotary race ways acting in alternation, and one of said race ways causing the tucker blades to direct a sheet between the folding devices and the other of said race ways causing the retraction of the tucker blades, the said race ways moving in a direction opposite to the direction of lateral movement of the tucker blades at the times and points of their operation thereon. 35
21. In a rotary folder, the combination of cutting and folding cylinders, a pair of folding rolls beside the folding cylinder, a shaft journaled in the folding cylinder carrying tucker blades and moved laterally by the cylinder, tumbling levers provided with pins attached to the opposite ends of said shaft, a rotary race way adjacent each end of the folding cylinder, and means for simultaneously rotating the said race ways, said rotary race ways acting in alternation and one of said race ways engaging one of the tumbling levers on the said shaft to cause the tucker blades to direct the sheet between the folding rolls, and the other of said rotary race ways engaging the other tumbling lever on said shaft to cause the retraction of the tucker blades, the said race ways moving in a direction opposite to the direction of lateral movement of the tucker blades at the times and points of their operation thereon. 40
- In testimony that I claim the foregoing as my own, I affix my signature in presence of two witnesses.
